ATTORNEY.

UNITED STATES PATENT OFFICE

SAMPSON W. MOON, OF CHICAGO, ILLINOIS, ASSIGNOR TO WILLIAM J. CAMERON, OF CHICAGO, ILLINOIS

OSCILLATORY MOTOR FOR ELECTRIC SAFETY RAZORS

Application filed November 18, 1929. Serial No. 407,836.

My present invention relates broadly to a vibratory apparatus and more particularly to a razor of the safety type that is operated through the medium of a vibrating armature. In constructing my present device I have assembled the parts so that the tool-carrying post and the actuating mechanism for vibrating the tool or blade are mounted upon a plug in the form of a unitary structure in order that they may be readily inserted in or removed from a tubular handle or grip. Another feature of the present structure is that the tool-post, which is exterior to the handle or grip, and the vibratory actuating mechanism which is within the handle or grip, are carried by the plug independently of each other, and the assembly of these parts is such that water or moisture is prevented from entering the handle and causing damage to the operating mechanism or short-circuiting the electrical elements.

My invention has numerous objects in view among which may be mentioned the provision of an electrically operated safety razor that is compact in construction; is novel in the arrangement of its parts; is dependable in operation, and is durable in construction. Further objects will be apparent after an understanding of my invention is had, and I prefer to accomplish said objects, and to carry out my invention, in substantially the manner hereinafter fully described and as more particularly pointed out in the claims. Reference will now be made to the accompanying drawings that form a part of this specification.

In the drawings:—

Figure 1 is a vertical longitudinal section of my improved safety razor, the view being taken axially therethrough.

Figure 2 is a vertical side elevation of the structure shown in Figure 1 showing the assembly with the handle or grip in section.

The drawings it will be understood are somewhat schematic for the purpose of illustrating a typical or preferred form in which my invention may be made, and in said drawings I have employed similar reference characters to designate like parts wherever they appear throughout the views.

The structure shown consists of an electro-magnet core 10 forming the body of a spool upon which there is an energizing winding 11 that has electrical connection at one end with core 10 in the usual manner, and the upper and lower ends of the spool are provided with retaining flanges 12 and 13 respectively. The upper or outer end of the core terminates in a head or pole 14 that is secured to the core by a screw, or in any other suitable manner. A pole piece 15, formed in a substantially L-shaped bracket, is secured to the lower end of the core, one arm of the pole piece or bracket being disposed along one side of the coil in the manner shown to support a flat spring 16 from which an armature bar 17 extends. The spring 16 is of magnetic material so that when the current is passing through the coil the armature bar will be attracted towards the upper pole piece 14 and the tension of the spring will pull the armature bar away from the pole piece causing vibratory movement of the armature and impacts upon the upper end of the structure resulting in a vibration of the handle in which the structure is removably mounted.

A yoke 18, of substantially U-shape and disposed with its parallel arms horizontal, has one of its parallel arms secured to the pole piece 14. This yoke is made of non-magnetic material, and the portion that connects the arms affords an abutment against which a hammer 19 on the end of the armature will strike when the armature is vibrated. In order to cushion the impact of the hammer against the abutment a buffer or cushion 20 of rubber or the like is interposed between the abutment and the hammer, and is preferably mounted in a socket in the latter. As will be seen the arms of the abutment yoke provide a space which accommodates the hammer 19 and thereby reduces the transverse dimensions of the structure.

The lower pole piece 15 has a pair of inner and outer contact springs 22 and 23 mounted upon the upright arm thereof and said springs are insulated from the latter

and from each other by pieces of insulating material 24.

The inner spring has its upper end pressing against the armature bar 17 about mid-way the length of the coil and it is insulated from said bar by an insulation block 25. This spring engages the outer spring through a contact block or point 26 when the armature bar is in a retracted position 10 and when the armature is attracted, the springs electrically disengage and the electro-magnetic energizing and actuating circuit opens.

The coil and the L-shaped pole piece 15 are secured to a base 27 of insulating material and a pair of terminal rods 28 and 29, of irregular shape extend through the base, the terminal 28 being connected by the wire or conductor 30 to one end of the energizing winding 11 and the terminal 29 being connected by a conductor or wire 40 to the lower end of the outer spring 23. The terminals 28 and 29 pass out of the lower end of the base 27 in spaced parallel relation to 25 each other so as to receive the socket contact elements on the end of an electric cord leading from a suitable source of current. The current passes intermittently through the make-and-break elements 26 on the ends 30 of arms or springs 22-23 and the spring 16 on armature bar 17 assists in creating the vibratory motion of the bar and vibrates the handle.

The structure hereinbefore described it 35 will be seen is practically a unit and in order to mount the same within a suitable handle I provide a plug 31 to which the upper horizontal arm of the abutment yoke 18 is connected by a screw 32. Imbedded 40 in the upper or outer portion of the plug is a tool-post 33 of any suitable design to receive a tool-head or blade-holder that may be removably attached thereto. The head or blade holder that is more particularly 45 adapted for use with the present structure is preferably of the type disclosed in the pending application of Arthur A. Grothe for patent for a "safety razor", filed November 18, 1929, Serial No. 407,830. The plug 50 31 is screw-threaded and is adapted to be inserted and screwed into the upper end of a tubular grip or handle 34 and after it has been screwed in the desired distance a cone-shaped cap 35 is mounted upon the plug in 55 the manner shown in Figure 2.

A plug 36 is screwed into the opposite end of the handle or grip and has an aperture 37 in order to accommodate the terminals 28 and 29. When the parts are being assembled 60 in the handle or grip the plugs are screwed towards each other until the base 27 abuts the lower plug 36.

What I claim is:-

1. A device of the character disclosed comprising a tubular handle, an electromagnet

herein, a plug removably secured in one end of said handle to which said electromagnet is connected, an abutment member interposed between said electromagnet and said plug and connected thereto, a vibratory armature actuated by said electromagnet to impact said abutment member and thereby vibrate said handle, a tool post mounted on said plug outside the handle and independent of the structure within said handle whereby it is caused to vibrate with said handle, and means closing the opposite end of said handle.

2. A device of the character disclosed comprising a tubular handle, an electromagnet therein, a plug removably secured in one end of said handle to which said electromagnet is connected, a base to which the opposite end of said electromagnet is connected, an abutment member interposed between said electromagnet and said plug and connected thereto, a vibratory armature actuated by said electromagnet to impact said abutment member and thereby vibrate said handle, a tool post mounted on said plug outside the handle and independent of the structure within said handle whereby it is caused to vibrate with said handle, and a plug in the opposite end of said handle with which said base is engaged.

3. A device of the character disclosed comprising a tubular handle, a removable plug closing an end of said handle, an abutment member secured to said plug and extending into said handle, an electromagnet core depending from said abutment member and provided with an energizing winding, a vibratory armature anchored adjacent the opposite end of said core and actuated thereby to impact said abutment member and thereby vibrate said handle, a tool-post mounted on said plug outside said handle and independent of the structure therein, whereby it is caused to vibrate with said handle, and closure means for the opposite end of said handle and engaged with the adjacent portion of said core to anchor the interior elements in position.

4. A device of the character disclosed comprising a tubular handle, a removable plug closing an end of said handle, an abutment member secured to said plug and extending into said handle, an electromagnet core secured to and depending from said abutment member and provided with an energizing winding, a base to which the opposite end of said core is connected, a vibratory armature anchored adjacent the opposite end of said core and actuated thereby to impact said abutment member and thereby vibrate said handle, a tool-post mounted on said plug outside said handle and independent of the structure therein, whereby it is caused to vibrate by said handle, and a plug in the opposite end of said handle with which said

base is engaged to anchor the interior elements in position.

5. A device of the character disclosed comprising a tubular handle, a removable plug closing an end of said handle, an abutment member secured to said plug within the handle, an electromagnet core secured to and extending from said member and having an energizing winding, a tool-post extending from the portion of said plug outside said handle and mounted independent of said abutment member and core whereby it is caused to vibrate when said handle is vibrated, a base to which the opposite end of 10 said core is connected, a vibratory armature anchored adjacent said base and core and actuated by the latter to impact said abutment member and thereby vibrate said handle, terminals extending through opposite 15 sides of said base and having electrical connection with said core and winding; the above-mentioned elements being assembled in a unitary structure for ready insertion in and removal from said handle; and a stop- 20 plug in the lower end of said handle that 25 is engaged by said base.

6. A device of the kind described comprising a hollow tubular grip, an abutment member adjacent one end of said grip, an 20 electromagnet core connected to said abutment and having an energizing coil, a vibratory armature bar extending alongside said coil and having its free end positioned adjacent said abutment, a head on said bar adapted 25 to impact said abutment when said bar is vibrated radially with respect to said coil, make-and-brake devices associated with said armature, circuit terminals having electrical connections with said coil and said make- 30 and-break devices, and a tool post on said grip.

7. A device of the kind described comprising a hollow grip, plugs closing the upper and lower ends thereof, an abutment member secured to the upper plug, a tool post anchored on said upper plug and extending out of said grip, an electromagnet core having an energizing coil, said core being anchored to the lower plug and connected at 45 its opposite end to said abutment, an L-shaped bracket having its lateral arm anchored on the lower plug and having its longer arm extending upwardly alongside said coil, an armature bar yieldingly carried 50 by said bracket and movable towards and away from said coil in a plane that is radial with respect to the core, make-and-break devices carried by said bracket and coacting 55 with said armature, and circuit terminals extended through said lower plug and having 60 electrical connections with said coil and said make-and-break devices.

Signed at Chicago, Cook County, Illinois,
the 9th day of October, 1929.

65 SAMPSON W. MOON.
